AUTOMOBILE DOOR HINGE

Ray A. Laible, Freeport, Ill., assignor of one-half
to Henney Motor Company, Inc., Freeport, Ill.,
a corporation of New York

Application August 14, 1948, Serial No. 44,359

4 Claims. (Cl. 16—135)

1

This invention relates to a new and improved automobile door hinge with hold-open and stop means incorporated therein.

Hinges embodying hold-open and/or stop means are, of course, well known generally speaking. However, many designs have not been practical either because of the undesirable effect upon the operation of the door, or because of the uncertainty of operation of the hold-open means, or the likelihood of breakage or quick wearing out of the part or parts relied upon, bearing in mind the fact that these parts are necessarily subjected to heavy load even under ideal operating conditions and rather violent shocks and jars under average conditions. The automobile manufacturers are, moreover, demanding that the hold-open and stop means add very little, if any, to the total cost of the hinge assembly, which, therefore, imposes a further serious limitation upon the design and construction of a commercially acceptable item of this kind. In the designing of the present hinge, all of these things had to be taken into consideration fully, with the result that I have provided a leaf spring on the inner hinge member having spaced arcuate end portions which are yieldable to admit therebetween the stop pin provided on the outer hinge member, so that the spring cushions the door as it reaches its limit of opening movement by exerting resistance to entry of the stop pin between the end portions, the stop pin serving, of course, positively to limit the opening movement, and the spring serving thereafter as a hold-open means yieldably resisting closing of the door. This construction meets the automobile manufacturers' requirements as to strength and durability and the hinge manufacturers' requirements as to low cost of production, besides meeting the motorists' requirements in regard to the door checking, stopping, and hold-open functions, which are performed positively and yet quietly and smoothly and without making the operation of the door the least bit difficult or awkward.

The invention is illustrated in the accompanying drawing, in which—

Fig. 1 shows an automobile door hinge, in horizontal section, equipped with a leaf spring and cooperating stop pin for hold-open, check, and stop purposes, in accordance with my invention, the hinge being shown in full lines fully opened, so as better to illustrate the operation, the closed position being indicated in dotted lines;

Fig. 2 is a vertical sectional detail on the line 2—2 of Fig. 1;

Fig. 3 is an isolated face view of the leaf spring, and

2

Fig. 4 is a fragmentary sectional detail corresponding to a portion of Fig. 1, but showing a modified or alternative construction.

Similar reference numerals are applied to corresponding parts in these four views.

Referring first to Figs. 1 to 3, the reference numeral 5 designates the outer, generally U-shaped, sheet metal hinge member that is mounted on the body of the automobile, and 6 the inner hinge member that is mounted on the door. The outer hinge member 5 being U-shaped provides opposed, substantially horizontal, parallel walls 7 and 8 interconnected by a substantially vertical wall 9. Embossed portions on the horizontal walls 7 and 8 form supports for the hinge pintle 10 received in a bearing hole 11 provided therefor in the inner end portion 12 of the inner hinge member 6. The walls 7 and 8 are also flanged outwardly at their outer ends to provide attaching portions for bolting, riveting, or otherwise securing the outer hinge member 5 to the body pillar. The generally U-shaped gooseneck portion 13 of the inner hinge member 6, of which the end portion 12 previously mentioned forms one side of the U, has a radius long enough so that the cross-portion 14 of the U clears the body pillar in the opening of the door, as clearly appears in Fig. 1, the door being free to swing through approximately ninety degrees (90°) from closed to open position, as can be seen from a comparison of the full line and dotted line positions of the inner hinge member 6 in Fig. 1.

In accordance with my invention, a stop pin 15 is provided in the outer hinge member in right angle relation to the top and bottom walls 7 and 8, and having reduced end portions 16 entered in holes 17 in the inwardly embossed portions 18 of said walls, the protruding portions of the pin being upset, as indicated at 19, to rivet the pin 15 permanently to the outer hinge member 5. I am aware that pins similarly located have been provided before, but, in accordance with my invention, this pin 15 cooperates in a novel manner with the inwardly bent arcuate end portions 20 and 21 of a generally U-shaped leaf spring 22 that is fastened to the outer side of the inner end portion 12 of the inner hinge member 6, as by means of a pair of bolts 23 entered through registering holes 24 and 25 provided in the spring 22 and hinge member 6 and threaded in holes provided in the opposite end portions of the elongated nut 26. Lock washers 27 are provided under the heads of the bolts 23 to minimize likelihood of their loosening in service. The nut 26 forms an abutment on the inner hinge member 6 for the stop pin 15, to positively limit the door

opening movement, and the arcuate end portions 20 and 21 of the leaf spring 22 are so spaced in relation to the diameter of the striker or stop pin 15 that the leaf spring cushions the door at the limit of opening movement instead of permitting the hinge member 6 to strike the pin 15 noisily and with a pronounced shock and jar, there being sufficient resistance afforded by the spreading of the end portions 20 and 21 in the entry of the stop pin 15 therebetween to give this door-checking action. Once the stop pin 15 has passed through between the arcuate end portions 20 and 21 of the leaf spring 22, it immediately encounters the abutment nut 26, which, of course, positively limits door opening movement, and the leaf spring 22 thereafter serves only as a hold-open means to resist closing of the door, it being manifest that the end portions 20 and 21 serve as hold-open means because they must be spread apart again in the initial closing movement of the door to allow the pin 15 to pass. The arrangement just described could, of course, be reversed, locating the stop pin 15 on the inner hinge member 6 and the leaf spring 22 on the outer hinge member, but it is obvious that the arrangement described and illustrated is preferable. Then too, the leaf spring 22 may be mounted on the outer hinge member and cooperate directly with the inner hinge member, when the latter is made of bar stock of a size to engage wedgingly between the ends 20-21 of the leaf spring, similarly as the pin in Fig. 1. Also, the arcuate end portions 20 and 21 instead of being bent inwardly as shown could be bent outwardly, although there again, the construction described and illustrated is preferable.

In Fig. 4 I have shown another construction, in which the same hinge members 5a and 6a are provided, and the same form of leaf spring 22 is mounted on the inner hinge member 6a by means of a pair of bolts 23 and a single elongated nut 26. However this hinge has, instead of the stop pin 15, a formed sheet metal striker 15a fastened on opposed bent in ears 28 provided on the upper and lower walls of the outer hinge member 5a, as by rivets 29. The striker 15a has a head portion 30 of hollow diamond shape on the end of a supporting shank portion 31, that has outwardly projecting attaching flanges 32 for riveting to the ears 28 of the hinge member 5a. The diamond shape of the head portion 30 that enters between the arcuate end portions 20 and 21 of the leaf spring 22 is of advantage from the standpoint of easier spreading of the arcuate end portions 20 and 21 of the leaf spring, both in entering and leaving the leaf spring in the opening and closing movements of the door, so that a stiffer leaf spring can be provided having a better door-checking action and a firmer hold-open action, without interfering with the easy operation of the door. Here again, it must be understood that the arrangement could be reversed, the striker 15a being provided on the inner hinge member instead of on the outer, and the spring 22 being provided on the outer hinge member instead of on the inner one. Also, the leaf spring 22 could be provided with reverse bending of the arcuate end portions 20 and 21.

It is believed that the foregoing description conveys a good understanding of the objects and advantages of my invention. The appended claims have been drawn to cover all legitimate modifications and adaptations.

I claim:

1. A combined door-hinging, door-stopping, and door-holding device comprising a stationary

outer hinge member of generally U-shaped form for mounting in a door supporting structure, an inner hinge member of gooseneck form attachable to a door and pivoted at its gooseneck end by a pintle between the arms of the U-shaped outer hinge member, a generally U-shaped leaf spring disposed with both arms of its U in the longitudinal plane of the gooseneck and fastened by its cross-portion to one side of the gooseneck in radially spaced relation to the pintle with the arms of the U-spring in part extending forwardly from the gooseneck in the direction of door opening movement, the outer end portions of the arms of the U-spring being formed to define with respect to a narrow throat in the open end of the U-spring opposed outwardly diverging walls and opposed inwardly diverging walls, and a cooperating striker fixedly mounted between the arms of the U-shaped outer hinge member in the path of swinging movement and at what corresponds to the open position of the gooseneck, said striker being of a width slightly greater than that of the narrow throat defined in the open end of said U-spring and arranged to have wedging engagement between said outwardly diverging walls in the opening of the door so as to spread the arms of said U-spring apart for a door checking action, said striker after passing through the throat having abutment within the U-spring positively to limit door opening movement and having contact with the inwardly diverging walls so as to hold the door open.

2. A combined door-hinging, door-stopping, and door-holding device comprising a stationary outer hinge member of generally U-shaped form for mounting in a door supporting structure, an inner hinge member of gooseneck form attachable to a door and pivoted at its gooseneck end by a pintle between the arms of the U-shaped outer hinge member, a generally U-shaped leaf spring disposed with both arms of its U in the longitudinal plane of the gooseneck and fastened by its cross-portion to one side of the gooseneck in radially spaced relation to the pintle with the arms of the U-spring in part extending forwardly from the gooseneck in the direction of door opening movement, the outer end portions of the arms of the U-spring being formed to define with respect to a narrow throat in the open end of the U-spring opposed outwardly diverging walls and opposed inwardly diverging walls, and a cooperating cylindrical striker pin fixedly mounted at its ends to the arms of the U-shaped outer hinge member in the path of swinging movement and at what corresponds to the open position of the gooseneck, said striker pin being of a diameter greater than the width of the narrow throat defined in the open end of said U-spring and adapted to have wedging engagement between said outwardly diverging walls in the opening of the door so as to spread the arms of said U-spring apart for a door checking action, said striker pin after passing through the throat having abutment within the U-spring positively to limit door opening movement and having contact with the inwardly diverging walls so as to hold the door open.

3. A device as set forth in claim 1, wherein the means for fastening the U-shaped leaf spring by its cross-portion to the outer side of the gooseneck comprises a pair of bolts entered through holes provided in the gooseneck and registering holes provided in the cross-portion of said spring and threaded in registering holes provided in an elongated nut disposed within said U-shaped spring

in abutment with the cross-portion, said nut being positively held against turning relative to either of said bolts by the other of said bolts and being so disposed relative to said throat and being of such size in relation to said U-spring and striker to serve as an abutment for said striker positively limiting opening of the door with the striker in engagement with the inwardly diverging walls of the open end of the U-spring.

4. A device as set forth in claim 2, wherein the means for fastening the U-shaped leaf spring by its cross-portion to the outer side of the gooseneck comprises a pair of bolts entered through holes provided in the gooseneck and registering holes provided in the cross-portion of said spring 15 and threaded in registering holes provided in an elongated nut disposed within said U-shaped spring in abutment with the cross-portion, said nut being disposed parallel to said striker pin and arranged for abutment of the pin the full 20 length of one side of said nut, said nut being positively held against turning relative to either of said bolts by the other of said bolts, said nut be-

ing so disposed relative to said throat and being of such size in relation to said U-spring and striker pin to serve as an abutment for said striker pin positively limiting opening of the door with the striker pin in engagement with the inwardly diverging walls of the open end of the U-spring.
